Primary Examiner — Rosemary K Tracza*Assistant Examiner* — Christy M Nemeth(74) *Attorney, Agent, or Firm* — Burr Forman McNair(57) **CLAIM**

The ornamental design for a battery pocket, as shown and described.

DESCRIPTION

FIG. 1 is a perspective view of a battery pocket of the present invention;

FIG. 2 is a front view of the battery pocket of FIG. 1;

FIG. 3 is a back view of the battery pocket of FIG. 1;

FIG. 4 is a left side view of the battery pocket of FIG. 1;

FIG. 5 is a right side view of the battery pocket of FIG. 1;

FIG. 6 is a top view of the battery pocket of FIG. 1; and,

FIG. 7 is a bottom view of the battery pocket of FIG. 1.

The broken lines in the drawings are for the purpose of illustrating environmental structure and portions of the battery pocket that form no part of the claimed design.

1 Claim, 7 Drawing Sheets(56)
